UNITED STATES PATENT OFFICE.

GEORGE W. LANCASTER, OF RICHMOND, VIRGINIA.

ELECTRICAL DEVICE FOR AUTOMATICALLY STOPPING TRAINS.

No. 892,271.

Specification of Letters Patent.

Patented June 30, 1908.

Application filed February 25, 1907. Serial No. 359,165.

To all whom it may concern:

Be it known that I, GEORGE W. LANCASTER, a citizen of the United States, residing at Richmond, in the county of Henrico and State of Virginia, have invented certain new and useful Improvements in Electrical Devices for Automatically Stopping Trains; and I do hereby declare the following to be a full, clear, and exact description of the invention, such as will enable others skilled in the art to which it appertains to make and use the same.

This invention relates to improvements in devices for automatically stopping trains, and particularly to electrically operated means that are adapted to be brought into operation when a train passes a signal set at danger.

The invention comprises the production of improved means mounted upon an engine that is adapted to be operated by current from an auxiliary track.

The invention further comprises the production of an auxiliary track, means for supplying an electrical current to said track when the signal along the track is set at danger, and means mounted upon the train for receiving electrical current from said rails for applying brakes to the train.

The object in view is the production of an electrically operated device that will automatically open the brake valve when the signals or semaphores are set at danger.

With these and other objects in view the invention comprises certain other novel constructions, combinations and arrangements of parts as will be hereinafter more fully described and claimed.

In the accompanying drawings:—Figure 1 is a view in elevation of the rear of a locomotive and a semaphore shown in connection therewith, the present invention being shown in connection with the semaphore and locomotive. Fig. 2 is a side elevation of a semaphore at safety showing broken the electric circuit which forms part of the present invention. Fig. 3 is an enlarged detail top plan view of an engineer's brake valve with part of the present invention applied thereto. Fig. 4 is an enlarged detail view of an engineer's valve showing a slightly modified way of attaching part of the present invention thereto. Fig. 5 is a fragmentary side elevation of a locomotive having a modified form of the present invention secured thereto.

The present invention relates to means for automatically stopping trains, and may be applied to any of the locomotives now in use without changing the same.

In order to clearly disclose my invention I have shown in the accompanying drawings an embodiment of my invention in which 1 represents an engine of any usual or preferred type provided with the usual engineer's valve 2. Mounted adjacent the engineer's valve 2 is a solenoid 3 having a reciprocating core 4. The core 4 has secured to its outer end a link 5 which in turn is pivotally secured to an extension 6 formed on the lever 7 of engineer's valve 2. If desired the extension 6 may be omitted and the link 5 pivotally mounted on the arm 7, at 8, but usually it is more convenient to have the extension 6 formed on the lever 7 and attach link 5 thereto as it then leaves lever 7 more free for the engineer to operate whenever desired.

From the solenoid 3 wires 19 and 10 pass downward to brushes 11 and 12 as clearly seen in Fig. 1. Suitable supporting means as arms 13 and 14 are provided for supporting brushes 11 and 12 in position. In order to secure a better contact, brushes 11 and 12 are provided with a plurality of contact points 15 and 16. The brushes 11 and 12 are rigidly positioned on the locomotive and are adapted to contact with auxiliary rails 17 and 18 when passing a signal, as semaphore 19. If current is being supplied to rails 17 and 18 when the locomotive passes the same brushes 11 and 12 will contact therewith and permit the circuit between the two rails to be closed through solenoid 3. As will be evident when solenoid 3 is energized it will rotate arm 7 and apply the brakes. If rails 17 and 18 are not provided with electrical current when the train passes the same, brushes 11 and 12 will contact with the same but will not complete a circuit for solenoid 3 and consequently the brake valve 2 is still held closed.

The rails 17 and 18 are supplied with electrical current from any suitable source as battery 20 when the semaphore 19 has its arm 21 set at danger. The arm 21 of semaphore 19 may be operated either by an automatic system, or by a switchman, as may be desired, the same not forming any part of the present invention. Rigidly secured to shaft 22 upon which arm 21 is mounted, is an arm

or extension 23 to which is rigidly secured a member 24 that is adapted to carry contact lugs or members 25 and 26. The member or cross arm 24 is made from any desirable insulating material so as to electrically insulate block or contact members 25 and 26 from each other. Blocks 25 and 26 are adapted to be moved in the arc of a circle by the movement of shaft 22 as clearly seen in Fig. 10 so as to be moved out of contact with blocks 27 and 28. Blocks 27 and 28 are insulated from the framework of the semaphore in any desirable way, and have secured thereto wires 29 and 30 which are in turn connected 15 to rails 17 and 18 respectively. Secured to blocks 25 and 26 are wires 31 and 32 respectively. Wires 31 and 32 are conveyed into the interior of the framework of the semaphore 19 through apertures 33 and 34, and from thence 20 in any convenient manner to battery 20. From this it will be observed that contact members 25 and 26 are continually connected with battery 20 but are insulated from each other, and will not form a complete circuit for 25 the battery until arm 21 of the semaphore is thrown to danger. When arm 21 is thrown to danger contact members 25 and 26 will contact with contact members or lugs 27 and 28. The contacting of the contact members 30 in this manner will connect wire 31 to wire 29, and wire 32 to wire 30. This will put rails 17 and 18 in electrical connection with battery 20, and when brushes 11 and 12 contact with rails 17 and 18 a circuit is completed through 35 solenoid 3. By the use of the contact members 25, 26, 27 and 28, and when the same are brought into contact upon the semaphore being thrown to danger, battery 20 will automatically charge rails 17 and 18 for acting 40 upon any trains that may attempt to pass said semaphore. In case the semaphore arm 21 is at safety or caution, the contact members 25, 26, 27 and 28 are out of contact and consequently rails 17 and 18 are out of connection with battery 20 so that a train passing the semaphore will not receive current through its brushes 11 and 12.

In Fig. 5 will be seen a slightly modified form of the present invention in which a solenoid 3' is mounted upon the air pipe 34, or if desired to any part of the engine adjacent to said pipe. A core 4' is provided for solenoid 3', to which is secured a link 5' which is preferably pivotally mounted upon core 4'. Link 5' is pivoted at its outer end at 6' to an arm or lever 7' which is adapted to operate a valve 2'. Valve 2' is positioned on air pipe 34 of the brake system, and is designed when open to exhaust air from the brake cylinders 60 for permitting the brakes to be applied. When the engine passes the rails 17 and 18, brushes 11 and 12 will contact therewith, and if the rails are charged will complete a circuit through wires 9' and 10' for energizing 65 the solenoid 3'. When the solenoid 3' has

been energized it will revolve valve 2' and permit air to escape therefrom for applying the brakes.

The present invention is adapted to be applied upon any system of signals now in use in which the signal is moved to danger and to safety, and it is adapted to be automatically operated by the signals as they are moved from one position to the other.

When the signal is at danger the present invention is operated so as to apply the brakes of the train if the same attempts to pass the signal that has been thrown to danger. The invention is equally adapted to operate trains running in either direction.

One of the important features of the present invention is the particular arrangement of parts that will permit the device to be placed in position and ready for operation without wasting substantially any electrical energy, and without using the same until it is ready to operate the brake operating mechanism.

What I claim is:

1. A device of the character described, comprising an electrically operated means mounted upon an engine for operating the air brake valve thereof, auxiliary rails, brushes contacting with said rails, connecting wires for providing a circuit between said rails and said electrically operated means, means for supplying current to said auxiliary rails, stationary contacts connected to said current supply means, movable contacts that are adapted to engage said stationary contacts and a pivotally mounted arm for carrying said movable contacts, said arm being adapted to be operated by a semaphore for moving said contacts for making and breaking the circuit.

2. A device of the character described, comprising electrically operated means upon an engine for operating the brake valves thereof, contact rails, brushes mounted upon said engine for contact with said rails, a source of current for supplying current to said rails, a plurality of movable contact members for connecting the circuit of said current, an insulating arm carrying said contact members, and an oscillating arm carrying said insulating arm, said oscillating arm being operated by the shaft of a semaphore, whereby when said semaphore is thrown to danger said source of current is connected to said rails.

3. A device of the character described comprising auxiliary rails, means for supplying current thereto, means mounted upon a locomotive for operating the engineer's air brake valve thereof, and means for connecting said rails and said valves and operating means, said valve operating means comprising a solenoid, a reciprocating core therefor, a link secured to said core at one end, and means for securing the opposite end of said

link to the arm of said air brake valve, and said link and means for securing the same to said core being adapted to permit said core to reciprocate freely and yet transmit rotary 5 movement to said valve.

4. A device of the character described, comprising an electrically operated means mounted upon an engine for operating the air brake valve thereof, a plurality of brushes 10 mounted on each side of the engine, and means connecting said brushes with said electrically operated means, auxiliary rails contacting with said brushes, means for supplying said rails with electrical current, 15 switch members interposed in said circuit, and a semaphore connected to said switch members for operating the same.

5. A device of the character described, comprising electrically operated means

mounted upon a locomotive for operating the 20 air brake valve thereof, means for supplying current to said electrically operated means, a semaphore for breaking the circuit of said current, said semaphore comprising a signal arm and an auxiliary arm secured thereto, a 25 cross bar secured to said arm, contact members secured to said cross bar, and contact members secured to said semaphore, the contact members on said cross bar and on said semaphore being adapted to be brought into 30 engagement with each other upon throwing the signal arm of the semaphore to danger.

In testimony whereof I affix my signature in presence of two witnesses.

GEORGE W. LANCASTER.
